UNITED STATES PATENT OFFICE.

WILLIAM E. MATHEWS, OF INDIANAPOLIS, AND ERNEST I. OREM, OF REXVILLE,
INDIANA.

COIN-CHANGING MACHINE.

1,101,206.

Specification of Letters Patent. Patented June 23, 1914.

Application filed June 14, 1911. Serial No. 638,013.

Be it known that we, WILLIAM E. MATHEWS and ERNEST I. OREM, citizens of the United States, residing at Indianapolis, county of Marion, and Rexville, in the county of Ripley, respectively, and State of Indiana, have invented a new and useful Coin-Changing Machine, of which the following is a specification, reference being had to the accompanying drawings and to the letters and figures of reference marked thereon.

This invention relates to a machine that is adapted to be used in business houses, such as banks, offices, mercantile houses or other places, for quickly and accurately changing coin into coin of smaller denominations, the invention having reference particularly to a cabinet that is adapted to stand in a convenient place, as on a counter or table, and contain quantities of different sizes of coins representing different money values which may be discharged from the cabinet upon the insertion into the cabinet of coins of larger sizes and denominations, the cabinet containing suitable coin-controlled mechanism to be operated by an attendant.

The object of the invention is to provide a reliable coin changing machine that may be so constructed as to be adapted to be cheaply produced and which shall be accurate whether or not the coins are of standard thickness; a further object being to provide apparatus of the above mentioned character that will enable business houses to conveniently change coined money without liability of errors and loss in transactions.

A specific object is to provide mechanical apparatus that will enable merchants to change the money of customers for them and then receive the exact amount of money from the customer required to cover the purchase of merchandise, so that there can be no mistake in returning the correct change to the customer.

A still further object is to provide a coin changing machine that will be so constructed as to enable the proprietor to readily keep a check on the value of the money handled.

The invention comprises a cabinet containing a plurality of rotatable magazines having each a plurality of coin receptacles, and mechanism for discharging the required

number of coins controlled by larger coins; and the invention consists further in the novel parts and combinations and arrangements of parts as hereinafter particularly described and claimed.

Referring to the drawings, Figure 1 is a perspective view of the improved coin changing machine; Fig. 2, a vertical sectional view taken through the foremost receptacles in the magazines; Fig. 3, a section on the plane of the line A A in Fig. 2 with the lower portion of the cabinet broken away; Fig. 4, a fragmentary section on the plane of the line B B in Fig. 3; Fig. 5, a fragmentary section on the line C C in Fig. 3; Fig. 6, a fragmentary horizontal section slightly below the line C C showing parts obscured in Fig. 5; Fig. 7, a fragmentary section on the line D D in Fig. 5; and Fig. 8, an inverted plan view of one of the coin magazines.

Similar reference characters in the different figures of the drawings indicate corresponding elements or features of construction herein referred to and described.

The case constituting a part of the cabinet preferably comprises a main portion and a removable cover portion, the main portion comprising a bottom 1, a front 2, a back 3 and sides 4 and 5. A suitable number of magazines 6, 6^a, 6^b, 6^c, 6^d, are employed and suitably supported rotatably and inclosed in the case, each magazine being cylindrical and of any desired length, all being equal in length however and arranged uprightly. Each magazine has a suitable number of coin receptacles 7 and 7' formed therein and extending therethrough longitudinally, the receptacles in the different magazines being of suitable diameter to receive coins of different diameters, as for instance the receptacles in one magazine have the required diameter to receive one-cent pieces, those in another magazine to receive ten-cent pieces, and so on. The wall of each cylinder preferably has longitudinal slots 8 therein, each slot extending from the periphery of the cylinder to the chamber adapted to hold the coins. Each slot preferably is somewhat narrowed at the lower portion of the cylinder, and recesses 9 are formed in the wall at opposite sides of the slots to receive a stop device for positioning the maga-

zine as required. The recesses however, may be formed in the wall elsewhere than in the slots if desired, the number of the recesses obviously depending upon the number of coin receptacles in the magazine.

The magazines may be constructed of wood in a simple and relatively cheap manner, in which case a suitable number of metallic plates 10 are forced into the lower end 10 of the cylinder so as to be flush with the end and they are arranged uniformly about the axis of the cylinder, one end of each plate being in contact with the middle portion of an adjacent plate, the plates being arranged 15 at oblique-angles each to the other, and recesses 11 are formed in the end of the cylinder adjacent the outer sides of the plates into which a pawl may be projected for periodically rotating the magazine, the plates 20 and recesses constituting the equivalent of a ratchet-wheel which, however, may be variously formed when the magazine is composed entirely of metal. Each magazine is provided with an axial shaft 12 which extends beyond the ends thereof, the ends of 25 the shaft preferably being pointed.

The different magazines and operating mechanism therefor are structurally independent of each other and arranged in different compartments in the case, as will further appear, so that a description in detail of one suffices for the others. In order to support each magazine and its operating and controlling mechanism, a pair of suitable guides 13 and 14 are arranged horizontally and extend from the back 3 to the front 2 and preferably to the plane of the outer face of the front, the guides being supported by the front and the back at a suitable distance apart. A suitable base 15 is fixedly supported on the two guides, and a plate 16 is secured upon the top of the base. The base has a shaft socket 17 therein and supports two standards 18 and 19 between which a magazine is arranged upon the plate 16, the shaft 12 extending into the socket through the plate for guidance. A bar 20 is secured upon the tops of the standards and is provided with a screw 21 having its lower end suitably shaped and seated upon the upper end of the shaft 12, constituting an adjustable bearing. The plate 16 has an aperture 22 therein arranged near the front 2 of suitable diameter to receive a coin of the size contained in the magazine, the plate being of the same thickness as the coin; or to compensate for inaccuracies the plate may be slightly thicker than the coin. Each base 15 has a guide channel 23 formed 55 therein at the sides of which are vertical guide faces 24 and 25. A suitable number of coin extractors 26, 26^a, 26^b, 26^c, 26^d, are provided, each of which is mounted slidably in one of the guide channels, the extractors being of different thicknesses and

the guide channels therefore being of different depths, so that the extractors fill the channels and fit closely under the plates 16. Each extractor has an aperture 27 therein which normally is in register with the aperture 22, the latter being in register with the foremost one of the receptacles in the magazine, so that a predetermined number of coins may be superimposed in the aperture 27 upon the base 15 to be moved by the extractor forward on the base and from under the coin remaining in the aperture 22. The extractor has a longitudinal slot 28 therein clearing the lower portion of the shaft 12. The forward portion of the extractor has two stop projections 29 and 30 thereon which engage the forward side of the base 15 to limit the inward or rearward movement of the extractor and accurately position the aperture 27. The inward or rearward end of the extractor has a downwardly projecting finger 31 thereon adapted to be engaged by a coin for moving the extractor forward to discharge the coin. In order to operate the extractors a suitable number of operating bars 32, 32^a, 32^b, 32^c, 32^d, are provided, each bar being suitably mounted slidably in the two guides 13 and 14 beneath the base that is mounted upon the guides, the operating bars extending nearly to the back 3 and also forwardly through the front 2, each bar being provided on its forward end with an operating handle 33 and also an upwardly extending lug 34 normally engaging the outer end of the extractor mounted in the base, the lug being adapted to retract the extractor. Each operating bar has an aperture 35 therein which under certain conditions of operation is brought under the aperture 27, to permit the coins to fall through the operating bar into a chute 36 secured to the front 2 below the bar. The under side of the operating bar has a longitudinal groove 37 therein which, in the rear end portion of the bar, extends through to the upper side of the bar to form a narrow slot, and a suitable ejector arm 38 has one end thereof connected to the front 2 by means of a pivot 39, the opposite end extending into the groove and being adapted to be forced upward into the slot by means of plate springs 40 and 40' secured to the front 2 and extending in contact with the under side of the arm, two springs preferably being employed so that the mechanism need not become disabled in case of fracture of one of the springs. The free end of the ejector arm normally rests in the bottom of the groove and can be forced upward into the slot only when the operating bar is projected forward. A spring finger 41 is mounted on the operating bar and extends upward through the slot 42 formed in the extractor 26 and also through a guide slot 42' formed in the plate 16, the end of the 130

finger resting against the under side of the plate when the bar is retracted and is projected upward into a recess 11 when the bar is projected forward to rotate the adjacent magazine. The operating bar 32 is forcibly retracted and normally held in retracted position by means of two coil springs 43 and 43' connected to the bar and also to the rearward portions of the guides 13 and 14 and must be pulled forward or projected by hand. A stop finger 44 is secured upon the extractor 26 and when the extractor is moved forward enters a recess 9, for accurately establishing the position of the magazine after it has been rotated, so as to bring a receptacle fair with the opening 22 in the plate 16.

A convenient arrangement of coins provides for holding one-cent pieces 45 in receptacles of the magazine 6, five-cent pieces 46 in the magazine 6^a, five-cent pieces 47 also in the magazine 6^a, ten-cent pieces 48 in the magazine 6^a and twenty-five cent pieces 49 or "quarters" in the magazine 6^a, the aperture in the extractor 26 holding five coins, the extractor 26^a holding two coins, the extractor 26^b holding five coins, the extractor 26^c holding five ten-cent coins, and the extractor 26^d holding four coins.

Reverting to the operating bar 32 it will be seen that the upper rear portion thereof has a recess 50 therein in which a coin 46 is inserted in Figs. 3, 4, 5 and 7, the coin being on edge and in Figs. 5 and 7 is carried forward against the finger 31 and has caused the extractor 26 to be moved forward nearly to the limit of its forward movement. Two connected curved guides 51 and 51' are mounted on the guides 13 and 14 and extend over the coin, the guides having slots 52 and 52' therein respectively, through which the coin will be ejected by the arm 38 when the ejector has been moved entirely forward. In order to place the coins in proper position in the operating bar a coin chute 53 is provided for each denomination of coin to be changed, the chute being arranged uprightly and having lugs 54 and 54' on opposite sides thereof, the upper portion above the lugs being connected to two slightly elastic upright rods 55 and 55' which are secured at their lower ends upon the guides 13 and 14, the lugs 54 and 54' being in contact with the forward sides 55 of the rods so as to tend to yieldingly hold the lower end of the chute forwardly, the lower end being provided with a lug 56 adapted to be engaged by the rear end of the operating bar 32 when retracted to push the lower end of the chute rearward slightly so that the chute will discharge the coin fairly into the recess 50. The chutes are of different diameters so as to admit only a predetermined size of coin and only a coin of limited diameter can be moved under the

guides 51 and 51', and if a coin of too small diameter is admitted it will pass under the finger 31 without operating the extractor. Preferably the forward side of the chute has a recess 53' therein which may be of proper proportion so as to permit the coin to pass through.

Preferably a guard plate 57 is placed rearward of each magazine and supported on projections 58 and 58' extending from the standards 18 and 19. Also in order to prevent the coins from falling into the mechanism when ejected from the operating bar a deflecting guard 59 is mounted on the guides 13 and 14 and is provided with a suitable guide tube 60 through which the coins are thrown, the guard having an opening 61 through which the chute 53 extends, a deflector 62 being secured to the chute and covering the opening 61 forward of the chute, so that the coins may drop upon the guard 59 and roll or slide off and fall at either side of the operating mechanism below.

The cover portion of the case comprises a front 63, sides 64 and 65 and a back 66, all being secured to a top 67 in which are coin receiving guides 68, 68^a, 68^b, 68^c, 68^d, for guiding different sizes of coins to the different chutes 53, the guides being designed to receive five-cent pieces 69, ten-cent pieces 70, twenty-five-cent pieces 71, fifty-cent pieces 72 and one dollar pieces 73, respectively, the designated characters being arranged on the top 67. The top 67 has a suitable number of partitions 74, 75, 76, 77, secured thereto and extending down between the different bases and magazines thereon to a distance corresponding to the plane of the top of a drawer 78 which is suitably supported in the case and has partitions 79, 80, 81, 82, therein immediately below the other partitions. The cover portion of the case is suitably fitted onto the upper end of the main portion of the case so as to be removable. Preferably an ordinary or suitable money drawer 83 is arranged on the bottom 1 of the case in which paper money or a reserve supply of coins may be kept. The drawer 78 preferably is inserted through the back 3 and provided with a lock 84. Preferably the cover portion of the case is locked to the main portion by means of the drawer 78, the sides 64 and 65 of the cover portion being provided with extensions 85 and 86, respectively, which project downward at the inner sides of the sides 4 and 5 of the main portion of the case and are provided at the lower ends with guides 87 and 88 adapted to slidably support the drawer 78, so that when the drawer is in normal position in the back 3 the drawer and consequently the cover portion cannot be lifted from the main portion of the case. The cover portion may be removed from the main portion 130

when the drawer 78 is entirely removed from the case.

In practical use the receptacles in the magazines are supplied with quantities of the various denominations of coins and the coins in the foremost receptacles are normally supported on the bases 15, the coins in the remaining receptacles being supported on the plate 16, when the machine is not in actual operation. In case it is desired to change one dollar into smaller denominations the one dollar piece is inserted into the guide 68^a and it falls down through the chute into the recess or holder 50, and then the attendant pulls the operating bar 32 forward, the bar in its movement carrying the coin against the finger 31 and forcing the extractor 26 forward with four twenty-five-cent pieces or quarters in the aperture 27 until the coins are moved forward beyond the front 2, when they drop through the registering aperture 35 into the chute 36 from which they may be received into the attendant's hand. When the extractor has moved the four coins from beneath the coin remaining in the aperture 22 the remaining coin is supported upon the extractor until the latter is returned to normal position, when the pile of coins in the next adjacent receptacle in the magazine which has been brought forward descends so that the four lower coins in the pile enter the aperture 21, it being understood that while the operating bar is moving forward the magazine is being rotated so as to carry the pile of coins in the foremost receptacle away from the coins that are in the apertures 22 and 27. When the controlling coin reaches the slots 52 and 52' it is ejected and forcibly thrown up through the guide 60 and falls into the compartment in the drawer 78 that is below the bar 32^a. Four quarters having been quickly obtained in exchange for one dollar, if it be desired to change a quarter into five-cent pieces it is inserted into the guide 68^b and the operating bar 32^b is then manipulated as before described, and five five-cent pieces are obtained. A five-cent piece, if desired, may then be inserted in the guide 68, and having manipulated the operating bar 32 it will be seen that five one-cent pieces are obtained. If it be desired to change a fifty-cent piece it is inserted in the guide 68^c and therefore five ten-cent pieces are obtained. If it be desired to change a ten-cent piece it is inserted in the guide 68^a and two five-cent pieces are obtained therefor.

Having thus described the invention what is claimed as new, is—

60 1. A coin-changing machine including a horizontally projectable coin extractor movably mounted and having an aperture in its forward portion for receiving and conveying coins, a coin-chute yieldingly supported uprightly and having its lower end spring-

pressed toward the extractor, the lower end having a lug thereon, an operating bar movable under the extractor and having a lug on its forward portion adapted for engaging the forward end of and retracting the extractor and having a recess therein to receive and carry a coin from the chute for engaging and projecting the extractor, the bar when retracted engaging the lug of the chute for registering the chute with the recess, and a spring for retracting the operating bar.

2. A coin-changing machine including a case, two guides supported in the case, a base secured upon the guides, an extractor longitudinally movable in the base and having an aperture adapted for receiving and moving coins, an operating bar movably mounted in the guides and having an upward extending lug thereon for engaging the forward end of and retracting the extractor, the bar having an opening therein in which is a recess to receive and carry a coin for engaging the rear end of and projecting the extractor, a guide for the controlling coin, and a spring-pressed device mounted in the case and movable upward into the opening when the extractor is projected for ejecting the actuating coin.

3. In a coin-changing machine, the combination of a base having a guideway in its top and a slot in its rear portion, a plate fixedly secured upon the base and extending over the guideway, the plate having a slot therein, a magazine rotatable on the plate, an extractor movable in the guideway under the plate and having a slot therein, an operating bar movably guided under the base, and a spring-finger mounted on the bar and extending upward and forward through all the slots to the magazine for rotating the latter.

4. In a coin-changing machine, the combination of a case, two guides horizontally supported in the case, a base horizontally secured upon the guides, an extractor movable in and partially beyond the base for receiving and moving coins, a chute supported in the case, an operating bar movably mounted in the guides under the extractor and having a receptacle therein to be carried under the chute to receive a coin for engaging and projecting the extractor, a coin-guide supported to extend over the bar for retaining the coin in the receptacle, a device movably mounted in the case for ejecting the coin upward from the receptacle, a spring mounted in the case for actuating the device, and a deflector supported by the base and extending over a portion of the operating bar and the coin-guide.

5. In a coin-changing machine, the combination of a case, a base fixed horizontally in the case, an extractor longitudinally guided upon the base, the outer end of the ex-

tractor normally being flush with and projectable beyond the outer side of the case, and an operating bar longitudinally guided under the base and normally projecting beyond the case, the bar having a pull handle on its outer end and having also an upward extending lug adjacent to the handle normally in contact with the case and the outer end of the extractor, the bar on forward movement carrying the lug away from the extractor, the inner portion of the bar having a receptacle therein beyond the inner end of the extractor to receive a coin to be carried forward to and move the extractor.

6. In a coin-changing machine, the combination of a horizontally movable extractor, a longitudinally movable operating bar under the extractor and having a pull handle on its front end, the rear portion of the bar having a longitudinal groove in the under side thereof and a narrow slot extending upward from the groove, the upper portion of said bar having a recess extending to the slot to receive a coin to be moved to the extractor for moving the latter, an ejector arm pivotally supported and extending into said groove and movable into said slot, and a supported spring seated on the under side of the arm and forcing the arm into said slot after movement of the extractor by the coin, to eject the coin from said recess.

7. In a coin-changing machine, the combination of a horizontally movable extractor, a magazine rotatably supported above the extractor, a longitudinally movable operating bar under the extractor and having a pull handle on its front end, the rear portion of the bar having a vertical opening extending therethrough, the upper portion of said bar having a recess extending to the said opening to receive a coin to be moved to the extractor for moving the latter, a supported ejector arm spring-pressed upward to the under side of said bar and movable into said opening to eject the coin from said recess after movement of the extractor by the coin, and a spring finger connected to said operating bar and extending forwardly

and upwardly through said extractor into operative engagement with said magazine. 50

8. In a coin-changing machine, the combination of a horizontal and longitudinally movable operating bar having a vertical opening extending therethrough, the upper portion of the bar having a transverse recess extending to said opening to receive a coin, two supported guides extending partially over said bar to retain the coin in said recess, a horizontal and longitudinally movable extractor above said bar and having a finger thereon extending downward between said two guides to be engaged by the coin to move the extractor on forward movement of said bar, and a supported ejector arm spring-pressed upward to the under side of said bar and movable into said opening to eject the coin from said recess after movement of the coin beyond said guides. 60

9. In a coin-changing machine, the combination of a case, a base fixed horizontally in the case, an extractor longitudinally guided upon the base and extending to the outer side of the case for receiving and moving coins, a chute supported in the case, an operating bar longitudinally guided under the base and normally projecting beyond the case, the bar having an upward extending lug on its forward portion normally in contact with the outer end of the extractor, the bar on forward movement carrying the lug away from the extractor, the inner portion of the bar having a receptacle therein beyond the inner end of the extractor and normally under the chute to receive a coin for engaging and projecting the extractor on forward movement of said bar, and a spring connected with the case and the operating bar for retracting said bar and enabling said bar to retract said extractor. 80

In testimony whereof, we affix our signatures in presence of two witnesses.
